BOX

George Siegel, Newark, N. J.

Application June 13, 1951, Serial No. 15,521

Term of patent 3½ years

(Cl. D58—14)

To all whom it may concern:

Be it known that I, George Siegel, a citizen of the United States, residing at Newark, in the county of Essex and State of New Jersey, have invented a new, original, and ornamental Design for Box, of which the following is a specification, reference being had to the accompanying drawing, forming part thereof.

In the drawing

Fig. 1 is a perspective view of a box, showing my new design;

Fig. 2 is a front elevation thereof; and

Fig. 3 is a side elevation thereof.

I claim:

The ornamental design for a box, as shown.

GEORGE SIEGEL.
